UNITED STATES PATENT OFFICE.

EDOUARD MAITRE, OF VEUXAULLES, FRANCE.

IMPROVEMENT IN WOODEN PANELS.

Specification forming part of Letters Patent No. **145,221**, dated December 2, 1873; application filed November 10, 1873.

To all whom it may concern:

Be it known that I, EDOUARD MAITRE, of the borough of Veuxaulles, in the Republic of France, have invented a new and useful Improvement in Wooden Panels; and I do hereby declare the following to be a full, clear, and exact description thereof, which will enable those skilled in the art to make and use the same, reference being had to the accompanying drawing forming part of this specification, in which drawing—

Figure 1 represents a face view of a panel made according to my invention. Fig. 2 is a similar view thereof in a modified form. Fig. 3 is a transverse section of the same. Fig 4 is a similar section of a modification thereof.

Similar letters indicate corresponding parts.

This invention relates to the manufacture of wooden panels for contabulations; and consists in the employment for this purpose of pieces of waste wood, which are united by means of tongues and grooves, and arranged in suitable patterns between entire boards, the whole being bolted together in such a manner that a compact and ornamental panel is obtained, which can be manufactured at a small cost, and finished for transportation.

In carrying out my invention I take pieces or strips, A, of wood, of that which usually goes to waste in a workshop, and provide the same with tongues and grooves, or with rabbets, whereby the same are joined together. These pieces are prepared by means of suitable machinery, to insure their uniformity and to reduce their cost of construction. The pieces A are interspersed with full or entire boards B, being more or less according to the stiffness required. In panels for flooring, requiring great strength, the stiffening-boards B are made to alternate with the pieced boards A, as in Fig. 1 of the drawing, but for ordinary

uses said stiffening-boards are placed only on one or both sides or edges of the panel, as in Fig. 2, thus affording a greater opportunity for display or ornamentation.

When the several parts have been adjusted in their relative positions, dowel-pins C are introduced for permanently holding the same together. Such dowel-pins are placed cross-wise, and are passed through the panel, as in Fig. 3, or keys may be arranged in guide-grooves, as in Fig. 4 of the drawing.

Colored woods may be employed in making my panels, the same being arranged in ornamental patterns, as wooden marquetry, and producing very beautiful effects.

The edges of the finished panel are cut off at right angles, or they may be cut off obliquely to form the contabulation called "Point of Hungary," and such finished panel is also provided with tongues and grooves to effect a connection.

The panels are entirely finished in the workshop, so that they are convenient for transportation, and the same may be substituted for tiles or enamel brick in flooring, and they are also of advantage for the construction of entablature friezes, wainscots, and other purposes.

What I claim as new, and desire to secure by Letters Patent, is—

In the manufacture of wooden panels, the employment of pieces or strips A of wood, which are united by means of tongues and grooves, and arranged in suitable patterns between entire or stiffening boards B, the whole being held together by means of pins or keys C, substantially as herein shown and described.

ED. MAITRE.
